FIG. 2.

FIG. 1.

INVENTOR
SIDNEY D. JACOBSON.

BY
Myron F. Hill
ATTORNEY

UNITED STATES PATENT OFFICE.

SIDNEY D. JACOBSON, OF NEW YORK, N. Y.

STABILIZING FLOAT.

1,405,036.

Specification of Letters Patent. Patented Jan. 31, 1922.

Application filed October 27, 1920. Serial No. 420,033.

To all whom it may concern:

Be it known that I, SIDNEY D. JACOBSON, citizen of the United States, and resident of New York city, in the county of New York and State of New York, have invented certain new and useful Improvements in Stabilizing Floats, of which the following is a specification.

My invention relates to a self stabilizing float for use in ships, and suitable for supporting beds, surgeon's operating tables, mounts for guns, or other heavy devices on board ship, for the purpose of counteracting to a considerable extent the effect of the movement of a ship at sea, particularly in rough weather.

In the drawings:

Fig. 1 shows a vertical section of my invention.

Fig. 2 shows a horizontal section upon the line 2—2 of Fig. 1.

My stabilizer consists in a receptacle 3 preferably a section of a hollow sphere as indicated in the drawings, upon a pedestal 4, is mounted or connected a platform 5, joined preferably by a universal joint 6. Beneath the platform is a float 8, preferably an air chamber, secured to the platform 5 by straps 9. 11 is a liquid seal as of leather or rubber.

The receptacle 3 is filled with water or other liquid to a level 10, sufficient to keel the platform 5 parallel with the plane of the surface of the liquid. As the ship provided with the above apparatus plunges and rolls the level 10 of the water in the holder tends to remain horizontal, which has the effect of keeping the platform 5 horizontal so that the rolling or pitching motions of a ship are not transmitted to the platform. The platform merely rises and falls with the ship.

Upon this platform may be located various objects, such as guns, surgeon's operating tables, or other heavy apparatus. It is for the purpose of rendering gun fire more accurate; for reducing the interference with surgeon's work, and where equipped as living quarters removing many of the motions tending to cause sea-sickness.

This apparatus may be of a size suitable

for the purpose for which it is intended and preferably located in a ship as near the center of gravity as possible to reduce the up and down motions of the apparatus as a whole.

Many variations of this invention may be made in its construction and details. The important features of my invention being set forth in the following claims.

What I claim is:

1. A stabilizing device comprising a platform, a liquid receptacle, a float therein carrying said platform, mechanical connecting means between the platform and receptacle adapted to permit the platform to maintain its level regardless of the motions of the receptacle and means to provide a freely movable and close joint between the surrounding edge of the float and the wall of the receptacle.

2. The combination claimed in claim 1 having said floating means including an air chamber supported under said platform around the connecting means.

3. The combination claimed in claim 2 having said float located under said platform.

4. The combination claimed in claim 1 having the interior of said receptacle concave in form and having said connecting means located in the center of said platform.

5. The combination claimed in claim 1 having the receptacle circular, the platform loosely fitting the same, and the connecting means in the center of the platform.

6. A stabilizing device comprising a receptacle, containing liquid a float therein provided with a supporting air chamber and means to provide a freely movable and close joint between the surrounding edge of the float and the wall of the receptacle.

7. The combination claimed in claim 1 having a spherical receptacle, the platform loosely fitting the same, and the connecting joint centered in the sphere.

8. The combination claimed in claim 1 having a spherical receptacle, the platform loosely fitting the same, and the connecting joint centered in the sphere, and a liquid seal between the platform and receptacle.

SIDNEY D. JACOBSON.
